HYDRAULICALLY OPERABLE STAPLE DRIVER
OR SIMILAR ARTICLEHerbert W. Marano, Summit, N. J., assignor to Wilson
Jones Company, Chicago, Ill., a corporation of Massa-
chusetts

Application November 16, 1955, Serial No. 38,929

Term of patent 14 years

(Cl. D74—1)

Figure 1 is a side elevational view of a hydraulically operable staple driver or similar article, showing my new design;

Figure 2 is a top plan view thereof;

Figure 3 is a front elevational view thereof;

Figure 4 is a rear elevational view thereof; and

Figure 5 is a bottom plan view thereof.

I claim:

The ornamental design for a hydraulically operable staple driver or similar article, as shown.
